(57) **CLAIM**

We claim the ornamental design for an inhaler, as shown and described.

DESCRIPTION

FIG. 1 is a perspective view of an embodiment of our design for an inhaler;

FIG. 2 is a front elevational view of the inhaler shown in FIG. 1;

FIG. 3 is a left side elevational view of the inhaler shown in FIG. 1;

FIG. 4 is a right side elevational view of the inhaler shown in FIG. 1;

FIG. 5 is a back elevational view of the inhaler shown in FIG. 1;

FIG. 6 is a top plan view of the inhaler shown in FIG. 1;

FIG. 7 is a bottom plan view of the inhaler shown in FIG. 1;

FIG. 8 is a perspective view thereof, with the cap removed;

FIG. 9 is a front elevational view of the inhaler shown in FIG. 8;

FIG. 10 is a left side elevational view of the inhaler shown in FIG. 8;

FIG. 11 is a right side elevational view of the inhaler shown in FIG. 8;

FIG. 12 is a back elevational view of the inhaler shown in FIG. 8;

FIG. 13 is a top plan view of the inhaler shown in FIG. 8; and,

FIG. 14 is a bottom plan view of the inhaler shown in FIG. 8.

The broken lines are shown for illustrative purposes only and form no part of the claimed design.
